US00D512969S

(12) **United States Design Patent** (10) Patent No.: **US D512,969 S**
Sato et al. (45) Date of Patent: **** Dec. 20, 2005**

(54) **TWIN AND PARALLEL DIODE WITH LEAD TERMINALS**

(75) Inventors: **Hirofumi Sato**, Kyoto (JP); **Kazunari Sato**, Kyoto (JP); **Koichi Fujii**, Kyoto (JP)

(73) Assignee: **Angel Co., Ltd.**, Kyoto (JP)

(**) Term: **14 Years**

(21) Appl. No.: **29/220,290**

(22) Filed: **Dec. 28, 2004**

(30) **Foreign Application Priority Data**

Jun. 28, 2004 (JP) D2004-019207

(51) LOC (6) Cl. **13-03**

(52) U.S. Cl. **D13/180**

(58) **Field of Search** D13/180; D26/2; 257/79, 80, 81, 82, 88, 89, 95, 98, 99, 100, 433, 434, 666; 313/483, 498, 500; 361/820; 362/235, 555, 800; 372/45

(57) **CLAIM**

The ornamental design for twin and parallel diode with lead terminals, as shown.

DESCRIPTION

FIG. 1 is a top view of twin and parallel diode with lead terminals showing our new design;

FIG. 2 is a bottom view thereof;

FIG. 3 is a front view thereof;

FIG. 4 is a rear view thereof;

FIG. 5 is a right side view thereof; and,

FIG. 6 is a left side view thereof.
